UNITED STATES PATENT OFFICE

HERBERT P. McGINNIS, OF PARKERSBURG, WEST VIRGINIA, ASSIGNOR TO GENERAL RAINCOAT CO., OF PARKERSBURG, WEST VIRGINIA, A CORPORATION OF WEST VIRGINIA

GARMENT

Application filed January 20, 1930. Serial No. 422,091.

This invention relates to garments and is directed more particularly to an improved coat having leg portions associated therewith.

5 The primary object of the present invention is to provide a coat having leg portions attached thereto in such manner that they may be easily and readily concealed beneath the coat or let down and applied to the legs of the wearer. The manner of attaching the leg portions to the coat being novel and of such character that the points of attachment shall not be visible from the exterior of the coat and hence when the legs 10 are folded beneath the coat, the coat from all exterior appearances shall be identical with any other coat.

Another object is to provide a coat of the above character which shall have the leg 20 portions attached thereto in such manner as to be adjustable for the height of the wearer and which may be folded when not in use in such manner that the soiled portions of the legs will not soil the clothing of the 25 wearer.

Another object is to provide a coat wherein the leg portions will be attached in such manner that they will not encumber or bind the wearer in any manner either in use or 30 in folded position.

A further object is to provide a coat wherein the leg portions may be easily and quickly detached so that they may be cleaned separately from the coat.

35 A still further object is to provide a coat of the aforesaid character which shall be simple in construction, inexpensive to manufacture, and which will afford complete protection from the weather to the wearer. 40 The foregoing and other objects and advantages will be realized as the description proceeds.

In the drawings accompanying and forming part of this application:

45 Fig. 1 is an illustration of a coat constructed in accordance with my invention with the leg portions unfolded and the coat and leg portions applied to the wearer;

50 Fig. 2 is an elevation of the interior of the coat; and

Figs. 3 and 4 are detail sectional views taken respectively on the lines 3-3 and 4-4 of Fig. 2.

Describing the various parts by reference characters, 1 denotes generally a coat of any suitable or approved style having the usual pockets. These pockets are formed in the body portions of the coat in the usual manner by slitting the material at 3 to provide an opening, and then fastening a pocket 4 55 and a flap 5 adjacent the opening by stitching or any other suitable fastening means.

Detachably connected to each pocket is a leg portion 6 adapted to loosely embrace the leg of the wearer to protect him against 60 the weather and since each of these leg portions are identical in construction a description of one is deemed to be sufficient.

Fastened along the lower side edges of each pocket are a plurality of snap fasteners 7 or other suitable attaching means which are adapted to engage with cooperating fasteners on the leg portion 6. Each leg portion is formed of suitable material, preferably similar to that from which the coat 75 is made, and is provided with a substantially tubular portion 9 adapted to loosely embrace the lower portion of the leg of the wearer, and a single thickness attaching portion 10. The tubular portion may be creased 80 like an ordinary trouser leg so as to be flat, and preferably the upper portion thereof is formed with a vent 11 that may be closed by a fastener 12. This vent serves to permit the wearer to conveniently step into or out 85 of the leg portion when the coat is being worn. As noted from Figs. 1 and 2, the tubular portion of the leg is preferably of such length that it always extends to a point above the lower edge of the coat. 90

When not in use, the leg portions may each be folded upon itself adjacent the top edge of the tubular portion so that said tubular portion lies between the coat and the attaching portion 10. Suitable fasteners 13 at the 95 lower end of the legs engage with cooperating fasteners 14 disposed along the side seams of the pockets adjacent their upper portions. It is thus apparent that the soiled or wet lower portion of each leg, namely the 100

tubular portion 9, when folded, is positioned between the coat and attaching portions and hence the wearer's clothing cannot be soiled thereby. If the leg portions become badly soiled, they may be easily and quickly detached from the pockets and cleaned separately from the coat.

In use, the leg portions will be folded beneath the coat and to all outside appearances, the coat is similar to any other due to the fastening of the leg portions to the pocket rather than the body of the coat. When desired, the fasteners 13 and 14 may be easily separated to let the legs fall down in position, whereupon fasteners 12 are unsnapped and the feet may be easily inserted through the tubular leg portions 9 while the coat is being worn. The leg portions protect the limbs of the wearer when so worn and being attached to the hanging pockets which are substantially waist high, permit free and easy movement of the legs without binding.

If desired, the leg portions may be permanently attached to the pockets, instead of using the detachable fasteners 7, when the coat is made to order for an individual. The coat and leg portions may be made of waterproof material to protect the wearer against rain or snow, or the coat and leg portions may be made of any woolen materials desired, to protect the wearer against cold.

I claim:

1. A garment of the character described comprising a body portion having pockets extending into and disposed on the inner side thereof, and leg covering elements attached to and supported entirely by certain of said pockets and adapted to embrace the legs of the wearer, the points of attachment being located on the inner faces of the pockets adjacent the coat.

2. A garment of the character described comprising a body portion having side pockets extending into and disposed on the interior side of the garment, leg covering elements connected to the marginal edges of said pockets, said leg covering elements each being formed with an upper flat attaching portion and a lower tubular portion, said elements each being adapted to be folded adjacent the line of intersection between said flat and tubular portions, and fastening means interposed between the coat and pocket for retaining said element in the folded position.

3. A garment of the character described comprising a body portion having side pockets extending into and disposed on the interior side of the garment, leg covering elements connected with said pockets, said leg covering elements each being formed with an upper flat attaching portion and a lower tubular portion adapted to embrace the leg of the wearer, said elements each

being adapted to be folded adjacent the line of intersection between said flat and tubular portions, and with the tubular portion disposed between the body of the garment and said flat portion, and fastening means for retaining said elements in folded position.

In testimony whereof I affix my signature.

HERBERT P. McGINNIS.
